CLAIM

The ornamental design for a sun visor dispenser, as shown and described.

DESCRIPTION

FIG. 1 is an elevational view of the rear face of the sun visor dispenser, containing the principles of the instant invention; FIG. 2 is an elevational view of the front face of the sun visor dispenser shown in FIG. 1;

FIG. 3 is an elevational view of the right end thereof;

FIG. 4 is an elevational view of the left end thereof;

FIG. 5 is a bottom plan view thereof;

FIG. 6 is a top plan view thereof;

FIG. 7 is a lower, front perspective view thereof; and,

FIG. 8 is an upper rear perspective view thereof.
